UNITED STATES PATENT OFFICE.

THOMAS WILBUR HIGHFILL, OF FARMER CITY, ILLINOIS.

WRENCH.

SPECIFICATION forming part of Letters Patent No. 761,961, dated June 7, 1904.

Application filed March 9, 1904. Serial No. 197,332. (No model.)

To all whom it may concern.

Be it known that I, THOMAS WILBUR HIGHFILL, a citizen of the United States, residing at Farmer City, in the county of De Witt and State of Illinois, have invented certain new and useful Improvements in Wrenches, of which the following is a specification.

This invention relates to improvements in wrenches having their movable jaws provided with teeth which are engaged by similar teeth on the shank, the engagement being effected by a cam, said cam being locked in position by an automatic catch.

The prime object of the invention is to provide a catch to lock the cam in fixed position after the movable jaw has been located on its shank.

In the drawings, Figure 1 is a perspective view of my improved wrench. Fig. 2 is a transverse section on the line 22, Fig. 3. Fig. 3 is a longitudinal section of the same.

1 represents a shank serrated on its edge to form teeth 1^a and having at opposite ends a fixed jaw 2 and a handle 3. A movable jaw 4 is adapted to be slid along the shank, and it consists of a biting portion 6, having its upper surface serrated to form teeth 7, and ears 8, extending upwardly from the said biting portion each side of and above the shank 1. The ears 8 carry perforations, through which a pin 10 passes. A cam-lever 11 is pivoted on the pin 10, and it is formed adjacent said pin with a cam 12, and extending outwardly therefrom is a finger-piece 13, by means of which the cam may be operated.

Fastened to the side of the shank is a spring-catch 15, formed at its upper end with an overhanging head 16, positioned to be at all times in the path of the finger-piece 13.

In operation the movable jaw is moved along the shank until the desired position is reached,

when the cam 12 is thrown down on the shank to draw the teeth 1^a and 7 into engagement to set the jaw, and in throwing down the finger-piece it forces the head 16 of the catch out of its path, whereupon as soon as said finger-piece passes the head the latter springs out and positively holds the cam down on the shank. The locking of the cam prevents accidental displacement while using the wrench, and thus enhances the value of the tool.

I am aware it is old in the art to use a cam to position the movable jaw of a wrench; but all of such devices are liable to become free at a critical time, and, as far as I am aware, it is new with me to lock the cam-lever after the latter is operated to fix the position of the movable jaw.

What I claim as new is—

A wrench comprising a stationary jaw, and a shank having a series of teeth, a toothed movable jaw slidably mounted on the shank, a slot formed in the movable jaw, a cam-lever pivoted in the slot, said lever lying flat on the shank when the teeth are in engagement to fix the movable jaw on the shank, and a spring-catch fastened to the side of the movable jaw, a head on the outer free end of the spring-catch which overhangs the shank and is in the radial plane of the cam-lever, said lever snapping under the head of the catch when it is thrown down on the shank, the lever freeing itself from its closed position on the shank when it is rocked and pushes the head out of its plane, substantially as described.

In testimony whereof I have signed my name to this specification in presence of two witnesses.

THOMAS WILBUR HIGHFILL.
